Primary Examiner—Jeffrey Asch(74) *Attorney, Agent, or Firm*—Nath & Associates PLLC; Gary M. Nath; Marvin C. Berkowitz(57) **CLAIM**

The ornamental design for a telephone set, as shown and described.

DESCRIPTION

FIG. 1 is a top plan view of a telephone set showing my new design,

FIG. 2 is a bottom plan view thereof,

FIG. 3 is a left side elevation view thereof,

FIG. 4 is a front elevation view thereof; and,

FIG. 5 is a rear elevation view thereof.

The handset and cord has been omitted from FIG. 5; and the cord has been omitted from FIGS. 2 and 4 for convenience of illustration. In FIG. 1 a feature has been shown extended to an open position.

1 Claim, 5 Drawing Sheets**FIG.1**

FIG. 2

FIG. 3

FIG. 4

FIG. 5
